BOILER FURNACE

Filed July 29, 1924

FIG. 1

FIG. 2

FIG. 3

INVENTOR
EDWARD T. RIST
BY
John W. Nelson
ATTORNEY.

UNITED STATES PATENT OFFICE.

EDWARD T. RIST, OF OELWEIN, IOWA.

BOILER FURNACE.

Application filed July 29, 1924. Serial No. 728,872.

To all whom it may concern:

Be it known that I, EDWARD T. RIST, a citizen of the United States, and a resident of Oelwein, county of Fayette, and State of Iowa, have invented certain new and useful Improvements in Boiler Furnaces, of which the following is a specification.

My invention relates to improvements in boiler furnaces and more particularly to improvements in refractory arches for use in locomotive furnaces having arch brick supporting members, as for instance, the familiar arch tubes.

The primary object of my invention is to improve and simplify the construction of such arches that they can be cheaply built, easily and quickly installed and maintained in efficient working condition with but little labor and expense.

Another object of the invention is to provide a multiple brick arch for locomotive fireboxes having arch supporting members, which shall require but a single form of brick for the entire arch, which brick are so constructed as to accommodate for variations in the width of fireboxes, and the irregularities in supporting members, irrespective of the number of said supporting members in each firebox.

A further object of the invention is to provide a form of brick which readily adapts itself to arranging the bricks in rows between adjacent supporting members, with each row comprising pairs of brick, having bearing engagement at one end upon the supporting members and a leaning relative supporting engagement with each other at the other end.

Still a further object of the invention is to provide a form of brick which is constructed at one end to have a bearing engagement upon the supporting member and which is constructed at the other end to fit into and have a leaning bearing engagement with the same end of another brick upon the placing of the brick in position upon the supporting members.

These objects of the invention, as well as others, together with the many advantages thereof will more fully appear as I proceed with my specification.

In the drawings:—

Fig. 1 is a longitudinal section through a

locomotive firebox equipped with an arch embodying my invention.

Fig. 2 is a transverse section through the arch tubes and associated parts as taken on the line 2—2 of Fig. 1.

Fig. 3 is an enlarged transverse section through the adjacent supporting members or arch tubes with a pair of my co-acting brick mounted thereon.

Fig. 4 is a perspective view of one of my improved brick.

Fig. 5 is a perspective view of a modified form of brick embodying my invention.

Referring now in detail to that embodiment of the invention illustrated in the accompanying drawings:—1 indicates the flue sheet of a locomotive furnace, 2—2 the side sheets, 3 the rear sheet and 4 the crown sheet of the furnace. The arch brick supporting members comprise, in this instance, arch tubes 5 which extend from the lower part of the flue sheet 1 to the upper part of the rear sheet 3, thus occupying an inclined position well adapted for the circulation of water from the front water leg 6 through said tubes into the rear water leg 7. The number of said tubes in an arch is, of course, dependent upon the size and type of locomotive, as well as other factors of construction thereof. While the arch is herein shown and will be herein described, as a front arch, I wish it to be understood that my improved arch is adapted for use, without material changes, as a rear arch.

From Fig. 2 of the drawings it is apparent that the supporting members or arch tubes 5 are substantially equally spaced from each other, the sidemost tubes 5 being arranged closer to the side sheets 2 than to the adjacent and in this instance, the center or intermediate tube 5. Such an arrangement is best adapted for brick of a uniform size but in many instances, other conditions arise in which this spacing is quite different.

The supporting members or tubes 5, in this instance, support a plurality of refractory bricks 8 which are arranged in two rows between adjacent tubes and serve to bridge and close the space between said tubes and form an arch or baffle wall. Each brick used herein is identical in form and construction so that a detailed description of one will suf-

face for all. Each brick is of a flat rectangular shape and preferably of a dimension greater in one direction than the other. The direction of greater dimension in this particular instance is referred to as the "length" which extends transversely of the furnace and the lesser dimension is referred to as the "width" which extends longitudinally of the furnace. The brick may or may not be of the same substantial thickness throughout its entire area and, as shown herein, said brick has plain or smooth top and bottom surfaces. By "smooth" in this instance I mean without intended corrugations or projections but, as is apparent, said top and bottom surfaces may be of any suitable or desired contour or form without departing from the spirit of the invention.

One of the ends of the brick is formed to provide a curved or grooved surface 9, as best shown in Figs. 3 and 4, which is adapted for a bearing engagement upon one of the supporting members or tubes 5. The opposite end of said brick is constructed to provide a semi-cylindrical tongue or extension 10 and a reversely curved groove or seat 11, both of which are of substantially the same diameter and extend the entire width of the brick. This end construction just described provides what may be termed a complementary end construction because when the bricks are arranged in operative relation in an arch, the extension 10 of one brick fits into the groove 11 of an associated brick in the manner of a hinge joint so that the bricks of each pair interengage with each other and provide a mutual leaning support, the one for the other. Such an interengaging and mutual leaning support is best shown in full lines in Fig. 3 where the bricks assume a substantial flat angle. However, when the tubes 5 are spaced closer together the bricks assume a more acute angle as shown in dotted lines in said figure, the interengaging parts of the brick of each pair providing for the relative change in angular position.

As shown in Fig. 2, certain of the brick rest upon the side tubes of the group and extend upwardly into engagement with the side sheets, and have a leaning support thereagainst with the end extensions or tongues 10 engaged with said side sheets.

In Fig. 5 is illustrated a slightly modified form of brick construction in what may properly be termed the tongue end thereof. Said end of the brick is increased in thickness as indicated at 12 so as to insure against chipping or breaking the same in the rough handling they naturally receive. In said figure the parts similar to those described in connection with Figs. 1 to 4, inclusive, have the same reference numbers.

It is apparent from the foregoing description that in my improved arch, a single

brick form serves with any number of tubes regardless of the irregularities of the spacing between said tubes. Furthermore, the bricks are of such form that they will readily pile up for storage purposes and this without danger of breakage thereto.

From the detailed description above set forth, it is believed that the objects and advantages of my novel and improved arch will be apparent to those skilled in the art, but since modifications may readily suggest themselves, I do not wish to be limited to the exact construction herein shown and described except as may be pointed out in the appended claims.

I claim:

1. In a locomotive firebox, the combination of a plurality of brick supporting members therein, bricks forming a refractory fire arch, with said bricks arranged in engaging pairs between adjacent brick supporting members, the brick of each pair having at one end a bearing surface to engage upon said supporting members and the other end of said brick of each pair having a half-round tongue on one side thereof and a quarter round groove in the other side thereof at the corner and extending entirely across the same so that the tongue of one brick may engage in the groove of the associated brick of the pair to provide a mutual leaning support, the one for the other.

2. In a locomotive firebox, the combination of a plurality of brick supporting members therein, bricks forming a refractory fire arch, with said bricks arranged in engaging pairs between adjacent brick supporting members, the brick of each pair having at one end a bearing surface to engage upon said supporting members and the other end of said brick of each pair having a half-round tongue on one side thereof and a quarter round groove in the other side thereof at the corner and extending entirely across the same so that the tongue of one brick may engage in the groove of the associated brick of the pair to provide a hinge-like engagement therebetween which permits of a varying spread of the other ends of said brick to accommodate the different spacings of said brick supporting members.

3. A brick for use in an arch of the kind described comprising a relatively flat rectangular body having a groove at one end and having at the other end a half round tongue on one side thereof and a quarter round groove in the other side thereof at the corner, which tongue and groove extend entirely across said end, and are so formed that the tongue of one brick may engage in the groove in the same end of another brick, and permit a relative angular adjustment between said bricks.

4. A brick for use in an arch of the kind

described comprising a relatively flat rectangular body having a groove at one end and having at the other end a half-round tongue on one side thereof and a quarter round groove in the other side thereof at the corner, which tongue and groove extend entirely across said end, and are so formed

that the tongue of one brick may engage in the groove in the same end of another brick, said last mentioned end of the brick being ¹⁰ thicker than the first mentioned end thereof.

In testimony whereof, I have hereunto set my hand, this 19th day of July, 1924.

EDWARD T. RIST.
